(57) **CLAIM**

The ornamental design for a computer microphone, as shown and described.

DESCRIPTION

FIG. 1 is a front, right side, top perspective view of a computer microphone showing my new design;

FIG. 2 is a rear, left side, bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines immediately adjacent to the shaded areas represent the bounds of the claimed design while all other broken lines depict environment that forms no part of the claimed design.

1 Claim, 8 Drawing Sheets
